SIGNALING APPARATUS.

1,413,748.

Specification of Letters Patent. Patented Apr. 25, 1922.

Application filed June 26, 1918. Serial No. 241,909.

To all whom it may concern:

Be it known that I, DIMMITT R. LOVEJOY, a citizen of the United States, residing at Freneau, Monmouth County, in the State 5 of New Jersey, have invented certain new and useful Improvements in Signaling Apparatus, of which the following is a full, clear, and exact specification.

This invention relates to improvements in 10 signaling apparatus of the non-interfering, successive type, such as are employed for sending signals from any one of a plurality of sending stations to a main or receiving station, and the same has for its object to 15 provide an apparatus of this type which will be efficient and reliable in its operation.

Further, said invention has for its object 20 to provide an apparatus of this character which will consist of but few parts, and which will be simple in its construction and inexpensive to manufacture.

Further, said invention has for its object 25 to provide an apparatus of this character comprising signal transmitting mechanism, and means for controlling the operation thereof.

Further, said invention has for its object 30 to provide an apparatus of this character comprising signal transmitting mechanism, movable means adapted in its operative position to prevent the actuation thereof, and electro-magnetically controlled means for normally holding said movable means in its inoperative position and maintaining the 35 same in said position during the actuation of the transmitting mechanism.

Further, said invention has for its object 40 to provide an apparatus of this character comprising signal transmitting mechanism, and means including a compound wound electro-magnet to control the operation of the transmitting mechanism.

Further, said invention has for its object 45 to provide an apparatus of this character comprising means for permitting communication between any one of the sending stations and the receiving station, without danger of interference from any of the others of the sending stations.

50 Other objects will in part be obvious, and in part be pointed out hereinafter.

To the attainment of the aforesaid objects and ends my invention consists in the novel details of construction, and in the combination, connection and arrangement of parts

hereinafter more fully described and then pointed out in the claims.

Referring to the accompanying drawing, illustrating, in diagrammatic form, a signaling apparatus embodying my invention, the 60 box transmission mechanism, which may be of any approved type, is shown as comprising a transmitter wheel 10 adapted to be driven by a gear train 11 when the operating lever 12 has been pulled and released, in the 65 usual manner. 13 and 14 indicate electrical contacts interposed in the signaling circuit and normally maintained in closed position by reason of the engagement of the contact 13 with the periphery of the transmitter 70 wheel 10. As the transmitter wheel 10 rotates, the recesses 15 formed therein will permit the contact 13 successively to move out of and into contact with the contact 14 to open and close the signaling circuit in 75 the well-known manner. It is of course understood, that the recesses 15 are arranged to correspond to the number of the box.

The escapement 16 of the box transmission mechanism, which controls the speed of 80 operation of the gear train 11, carries an arm 17. Pivotedly supported adjacent the free end of the arm 17, is a lever 18 having a projection 19 at one end thereof adapted to be moved into or out of engagement with 85 the free end of the arm 17, whereby to prevent or permit the actuation of the ratchet escapement 16 and the gear train 11 controlled thereby. In order to insure that the projection 19 will engage the end of the 90 arm 17 at one or the other of the sides thereof, the projection 19 and the arm 17 are provided with co-acting knife-edges, as shown.

The lever 18 is so mounted and arranged, as for example by weighting its 95 other end, that it normally tends to occupy its operative position, with the projection 19 in engagement with the arm 17. The lever 18 is normally held in its inoperative position by means of a pin 20, which engages the weighted end of the lever 18 and is carried by a vertically movable rod 21, normally held in its raised position and adapted to be actuated to control the movement of the lever 18 as hereinafter described.

Adjacent its upper end, the rod 21 is provided with a pin 22, upon which rests the free end of a pivotally supported armature 23, of a compound electro-magnet 24 having a low resistance winding 25 connect- 110

ed in series with the normally closed contacts 13, 14, and a high resistance winding 26 connected in shunt with the normally closed contacts 13, 14. An adjustable stop 5 27 is provided to limit the downward movement of the armature 23. A spring 28 has one of its ends connected to the armature 23 and its other end connected to a pin 29 carried by the rod 21. At its lower end 10 the rod 21 carries a pawl 30 which engages the teeth of the gear wheel 31 forming part of a gear train 32 comprising means for retarding the actuation thereof, as, for example, a pinion 33 carrying vanes 34.

15 35 indicates a telegraph key comprising a contact 36 and a lever 37 normally held in engagement with the contact 36 by means of a spring 38.

One of the conductors 39 of the signaling 20 circuit is connected to the contact 14, and the other conductor 40 of said circuit is connected to the lever 37 of the telegraph key 35. A conductor 41 connects the contact 36 of the telegraph key 35 to one end of the 25 series winding 25 of the electro-magnet 24, and the other end of the series winding is connected to the contact 13 by a conductor 42. The ends of the shunt winding 26 are connected to the conductors 39 and 42, by 30 the conductors 43 and 44 respectively.

It is, of course, understood that a plurality 35 of signaling apparatus may be interposed in series in the signaling circuit at different stations, as is the common practice, and that the construction and wiring connections of 40 each such apparatus is the same as that above described.

Under normal conditions the telegraph 45 key 35 is closed and the contacts 13 and 14 are in contact with one another, as hereinabove described, and, therefore, there will be a continuous flow of current through the following path:—conductor 40, lever 37, contact 36, conductor 41, series winding 25 50 of the electro-magnet 24, conductor 42, contacts 13 and 14, and conductor 39. No current will flow through the shunt winding 26 of the electro-magnet 24 as the same is short-circuited by the normally engaged contacts 13 and 14. The current flowing 55 through the series winding 25 energizes the electro-magnet 24 thereby holding its armature 23 in its raised position. The spring 28 will hold the rod 21 in its raised position 60 in which position the pin 20, carried thereby and engaging the weighted end of the lever 18, will hold the lever 18 in its inoperative position with the projection 19 at its other end out of engagement with the end 65 of the arm 17, carried by the ratchet escapement 16.

The operation is as follows:—

When a signal is to be sent, the operating 65 lever 12 of the box transmission mechanism is pulled and released, thereby actuating the

gear train 11 and causing the same to rotate the transmitter wheel 10 in the usual manner. When the first one of the recesses 15, formed in the transmitter wheel 10, moves into register with the contact 13, said contact will drop into the recess and out of engagement with the contact 14, thereby breaking the signaling circuit at this point, and compelling the current to flow through the following path at the signaling station:— 75 conductor 40, lever 37, contact 36, conductor 41, series winding 25, conductor 42, conductor 44, shunt winding 26, conductor 43, and conductor 39. At all other stations in the signaling circuit the current will continue 80 to flow through its normal path, in which it passes through the series windings only of the several electro-magnets. Owing to the high resistance of the shunt winding 26 through which the current now flows at the 85 sending station, the strength of the current flowing through the signaling circuit will be greatly decreased, but, owing to the fact that the current at the sending station now flows through both the series winding 25 90 and the shunt winding 26, the energization of the electro-magnet 24 will be sufficient to hold the armature 23 at the sending station in its raised position. The rod 21 will therefore be held in its raised position, and the 95 pin 20 carried thereby will hold the lever 18 in its inoperative position. The series winding 25 of the electro-magnet 24 is so proportioned and constructed that, when the current of decreased strength flows there- 100 through, the electro-magnet 24 will not be energized sufficiently to retain its armature 23 in its raised position, and, consequently, at every station on the circuit, other than the sending station, the armature 23 will 105 drop from its normally raised position until it engages the stop 27. As the armature 23, at each of the other stations, drops, the rod 21 will move downwardly and the lever 18 will thereupon be permitted to assume its 110 operative position with the projection 19 engaging the end of the arm 17 carried by the ratchet escapement 16, thereby preventing the actuation of the same and of the gear train 11 controlled thereby. The downward movement of the rod 21 will also cause the pawl 30 to ride over the teeth of the gear wheel 31 and to engage with a tooth below that one with which it engaged when the rod 21 was in its raised position. 115

As the transmitter wheel 10 at the sending station continues to rotate, the contact 13 will ride out of the first of the recesses 15 and will again come into contact with the contact 14, thereby short circuiting the 125 shunt winding 26 of the electro-magnet 24 at the sending station and permitting the full, normal strength of current to again flow through the signaling circuit. This change in the strength of the current will 130

- have no effect with respect to the sending station, as the armature 23, and its co-acting parts, were maintained in their normal positions when the strength of the current 5 was reduced. At each of the other stations on the circuit, however, as soon as the current flowing therethrough assumes its full strength, the armature 23 is immediately attracted and raised to its normal position. 10 As the armature 23 thus moves to its normal position, it tends to raise the rod 21 to its normal position by means of the spring 28, but the upward movement of the rod 21 is retarded by reason of the fact that the 15 pawl 30 is in engagement with a tooth of the gear wheel 31 of the retarding gear train 32. The rod 21, therefore, has a slow upward movement and before it can rise sufficiently to move the lever 18 out of locking 20 engagement with the arm 17 of the ratchet escapement 16, the contact 13 at the sending station will have dropped into the next succeeding one of the recesses 15 of the transmitter wheel 10, whereupon the 25 strength of the current in the circuit will again be decreased, as above described, as a result of which the armature 23 at each of the other stations will again drop, and the rod 21 will move from its partially raised 30 position to its lowermost position. This operation of the apparatus at the stations other than the sending station is repeated as the contacts 13 and 14 at the sending station make and break contact with one another during the rotation of the transmitter wheel 10. The retarding gear train 32 is preferably so constructed, and the operation thereof is so timed, that the time required by the rod 21 to rise from its lower- 35 most position to a position in which it will render the lever 18 inoperative will be at least equal to the time required for one complete rotation of the transmitter wheel 10. This will insure that no station on the circuit can interfere with a sending station. 40 When the transmitter wheel 10 at the sending station comes to rest, after having sent the signal one or more times, in the usual manner, the engagement of the contact 13 with the contact 14 again permits the full strength of current to flow through 45 the circuit. The armature 23 at each of the other stations will be attracted to its raised position, and the rod 21 at each of said stations will now be permitted to be drawn upwardly to its normal position by the spring 28, whereupon the pin 20 carried thereby will cause the lever 18 to assume its inoperative position, and a signal may then 50 be sent from any one of the stations in the circuit.
- If, during the sending of a signal from one of the stations on the circuit, the operating lever 12 at any other station is pulled 55 and released, the transmission mechanism 60
- at said other station can not operate, as the lever 18 has moved into its operative or locking position, as above described, but after the signal from the sending station has been completed, the locking lever 18 at said other station will be moved to occupy its inoperative position, and, as soon as this occurs, the transmission mechanism at said other station will thereupon be free to operate to send a signal. 70
- If the fire chief, or any other authorized person, wishes to communicate with headquarters, he can do so by means of the telegraph key 35 without danger of interference from any one of the sending stations 75 on the circuit. Upon depressing the lever 37, at the beginning of the message, the signaling circuit is broken between the lever 37 and contact 36 and the armature 23 at each station drops, thus causing the lever 18 80 to lock the transmission mechanism at each station against operation, as above described. During the sending of the message the interval of time between the letters or words transmitted will not be sufficient to permit 85 the bars 21 at the several stations to rise sufficiently to cause the levers 18 to move to their unlocking positions, and therefore, the sending of the message cannot be interfered with. Messages from headquarters may be 90 received by means of the electro-magnet 24 which will operate as a sounder. The actuation of the circuit closer at headquarters will cause the armature 23 to respond to the 95 telegraph signals transmitted from the circuit closer at headquarters. The bars 21 at the several stations will not be actuated to operate the levers 18 as above set forth. 100
- Having thus described my said invention what I claim and desire to secure by Letters Patent is:—
1. An apparatus of the class described comprising a signal transmitting mechanism, means movable into and out of operative relation to said transmitting mechanism 110 to control the actuation thereof, means responsive to an electric current for normally holding said movable means in its inoperative position and adapted to permit said movable means to assume its operative position when the current strength is decreased below a predetermined value, and means co-acting with said holding means to maintain said movable means in its inoperative position when the current strength 115 is so decreased, substantially as specified.
  2. An apparatus of the class described comprising a signal transmitting mechanism provided with a normally closed make and break device, electro-magnetic means 120 comprising a coil in series with said make and break device, and a coil in parallel with said make and break device and in series with said first-named coil, and means controlled by said electro-magnetic means 125 130

for controlling the operation of said transmitting mechanism, substantially as specified.

3. An apparatus of the class described comprising a signal transmitting mechanism provided with a normally closed make and break device, electro-magnetic means comprising a low resistance coil in series with said make and break device, and a high resistance coil in parallel with said make and break device and in series with said low resistance coil, and means controlled by

said electro-magnetic means for controlling the operation of said transmitting mechanism, substantially as specified.

Signed at the city of New York, in the county and State of New York, this 5th day of June, one thousand nine hundred and eighteen.
